The ornamental design for a rotating spinner irrigation sprinkler, as shown and described.

DESCRIPTION

FIG. 1 is a perspective view taken from the top, front right side of a rotating spinner irrigation sprinkler embodying my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof;

FIG. 7 is a left side elevational view thereof with portions of the support bridge broken away to show portions not otherwise seen;

FIG. 8 is a cross-sectional view thereof taken substantially along the line 8—8 of FIG. 3; and,

FIG. 9 is a cross-sectional view thereof taken substantially along the line 9—9 of FIG. 3.

The broken line representation of a nozzle in FIG. 1 is for purposes of illustration only and forms no part of the claimed design.
